UNITED STATES PATENT OFFICE.

EVERARD RICHARD CALTHROP, OF LONDON, ENGLAND, ASSIGNOR TO E. R.
CALTHROP'S AERIAL PATENTS LIMITED, OF LONDON, ENGLAND.

PARACHUTE.

1,369,395.

Specification of Letters Patent. Patented Feb. 22, 1921.

Application filed September 8, 1919. Serial No. 322,496.

To all whom it may concern:

Be it known that I, EVERARD RICHARD CALTHROP, a subject of the King of Great Britain, residing at London, in the county 5 of Middlesex, England, have invented new and useful Improvements Relating to Parachutes, of which the following is a specification.

This invention relates to parachutes of the 10 kind adapted to be carried in a container secured to the person of the aviator.

The object of the invention is to provide a simple and efficient device flexible and cushion-like as to its mass and its container 15 more readily stowable and not subject to indentation from rough usage as is the case with metal containers whereby a parachute may be carried by an aviator in such a manner that in an emergency it will be instantly 20 launched and when used with an aeroplane from either side of the fuselage to support the aviator and permit of an easy and safe descent to the ground.

According to the present invention the 25 device is adapted to be secured to the person of and carried directly by the aviator knapsack fashion for which purpose its resiliency and flexibility renders it particularly suitable. A two part casing or container is provided the lower part of which is secured 30 to the harness worn by the aviator while the upper portion of said casing is attached by an appropriate connection to a suitable part of the aeroplane. The two part casing or 35 container is constructed of flexible material such as rubberized fabric which may if desired be reinforced by means of wires or otherwise. The mouth of the upper portion of the container is rendered rigid such as by 40 means of an annular member which may be constituted by a metal tube or the like and the lower part is adapted to overlap said annular member in such a manner as to insure a weather tight joint.

The 45 parachute employed in connection with the present invention is substantially similar to that described in my prior specification 1291762, said parachute being nested within the aforesaid two part casing or 50 container the lower portion of which supports the packed rigging tapes.

In the accompanying drawings:—

Figure 1 represents more or less diagrammatically a vertical section through a parachute launching device embodying this in-

vention a portion of the harness worn by the aviator being also shown.

Fig. 2 is a diagram illustrating the improved parachute launching device shown in Fig. 1 in operation.

In that embodiment of the invention illustrated in Fig. 1 the container for the nested parachute 1 comprises an upper portion and a lower portion designated respectively by the reference numerals 2 and 3 and constructed of flexible material such as rubberized fabric which may if desired be reinforced by means of wires or otherwise. The lower part 3 of this bi-part container is positively attached to the aviator's harness 4 while the upper portion 2 is adapted for attachment to the aircraft such as by means of a rope 5 engaged with the suspension member 6. The edges of the two portions of the container are overlapped when in operative relation to each other to form a weather tight joint as will be well understood by those familiar with the nested type of parachute to which this invention relates. Located within the mouth of the upper portion 2 of the container is an annular member 7 which may be of wood or metal or may be tubular to reduce the weight of the device as a whole and the function of this ring 7 is to maintain the mouth of upper portion 2 of the container rigid when the parts are assembled as shown in Fig. 1 and also to permit the plaited and folded body 1 of the parachute to emerge from the portion 2 of the container without obstruction when the load is applied as will hereinafter be explained.

The ring 7 may be positively secured to the annular edge of the portion 2 of the container but preferably said portion 2 is constructed to frictionally engage or grip the ring 7 and hold it in position the ring being positively connected to the portion 2 at its apex by a plurality of tapes or the like 2 secured to the suspension member 6.

The parachute body 1 is compactly plaited and folded and arranged within the portion 2 of the bi-part container together with its rigging which is composed of tapes arranged in packs two of which latter are indicated at 9. The apex of the body 1 is connected by 100 rupturable connections 10 with the suspension member 6 and the ends of the rigging tapes are positively connected with what may be termed the center fitting 11 to which one end of the suspension or load rope 12 is 105 110

secured the opposite end being secured to the harness 1 by means of the loop 13 provided for that purpose. The two portions of the container are retained in operative relation by the wire or other rupturable connection 14 attached respectively to the suspension member 6 and the center fitting 11.

The type of parachute which I prefer to employ in connection with the herein described launching device is substantially similar to that described in my specification of prior date No. 1,291,762 and it is therefore unnecessary to more than briefly refer to it here as its construction and operation are described in detail in the aforesaid prior specification but it may be mentioned that in employing such type of parachute in connection with the present invention I dispense with the means described in the prior specification for controlling the speed of descent of the parachute and its load.

I will now proceed to a consideration of the operation of my improved launching device. The bi-part container being secured 25 to the aviator as above described and the rope 5 made fast to the aircraft when a descent is to be made the aviator jumps from either side of the cockpit whereupon his weight will be transferred to rope 5 connecting the upper portion 2 of the container to the aircraft.

When the said rope becomes taut the weight will be transferred through the harness 4 to the load rope 12 and the center fitting 11 and the wire or like rupturable connection 14 will snap thus allowing the lower cover 3 to separate from the upper portion 2. The rigging tapes 9 will now be extended against the resistance of the breaking pieces 15 which are attached to the ring 7 and to the toggles 16 which serve to connect the rigging tapes 9 with the periphery of the parachute body 1. These breaking pieces form no part of the present invention 45 *per se* as they are fully described in my

aforesaid prior specification, but it will be observed from an inspection of Fig. 2 that they have the effect of abstracting the periphery of the parachute body in a circle thus insuring the entry of air to the interior 50 of said body to make certain its complete expansion. As these several operations are taking place the ring 7 will have fallen until arrested by its supporting tapes 8 and when the breaking pieces 15 are extended to their 55 full length they will snap dissynchronously as they are of different lengths under the strain exerted upon them by the weight of the load and the rupturable connections 10 at the apex of the parachute body will also 60 snap thereupon the parachute will be free to expand to its full extent to safely support the aviator in his descent to the ground the upper portion 2 of the container remaining suspended from the aeroplane. 65

I claim:

1. A parachute launching device comprising a bi-part flexible container a parachute nested within said container means for positively attaching the upper part of said container to the aircraft means for positively attaching the lower part of said container to the person of the aviator a load rope positively secured to the parachute and to the aviator and means for temporarily maintaining rigid the mouth of the upper portion of said container. 70

2. A parachute launching device comprising a bi-part flexible container a parachute nested within said container means for positively attaching the upper part of said container to the aircraft means for positively attaching the lower part of said container to the person of the aviator a load rope positively secured to the parachute and to the 80 aviator and an annular member detachably supported within the mouth of the upper portion of said container. 85

EVERARD RICHARD CALTHROP.
